HOUSING FOR AUXILIARY VEHICLE LIGHTS

August B. Meyer, Cincinnati, Ohio, assignor to K-D
Lamp Company, Cincinnati, Ohio

Filed Mar. 22, 1971, Ser. No. 127,089

Term of patent 14 years

Int. Cl. D26—06

U.S. Cl. D48—32 R

FIG. 1 is a frontal elevational view of a housing for auxiliary vehicle lights showing my new design;

FIG. 2 is a top plan view thereof;

FIG. 3 is a right end elevational view thereof;

FIG. 4 is a rear elevational view thereof.

The stippling is partially shown on the housing for convenience of illustration and is continuous over the surfaces where it is indicated. The stippling on the interior surfaces of the two large lamp cups appears through the lenses in FIG. 1.

I claim:

The ornamental design for a housing for auxiliary vehicle lights, substantially as shown and described.
